DESIGN FOR AN ACROBATIC APPARATUS

Raymond W. Copeland and Lela D. R. Copeland,
Moraga, Calif.

Application April 22, 1942, Serial No. 106,660

Term of patent 7 years

To all whom it may concern:

Be it known that we, Raymond W. Copeland, a citizen of the United States and a resident of Moraga, in the county of Contra Costa and State of California, and Lela D. R. Copeland, a citizen of the United States and a resident of Moraga, in the county of Contra Costa and State of California, have invented a new, original, and ornamental Design for an Acrobatic Apparatus, of which the following is a specification, reference being had to the accompanying drawing, forming a part thereof, in which:

Fig. 1 is a view in perspective of an acrobatic apparatus showing our new design;

Fig. 2 is a side elevational view; and

Fig. 3 is a cross sectional view taken on the line 3—3 of Fig. 1.

We claim:

The ornamental design for an acrobatic apparatus, substantially as shown.

RAYMOND W. COPELAND.
